QUENCHING DEVICE FOR QUENCHING THE
ENDS OF ABUTTING RAILS IN A TRACK
JOINT

Daniel G. Kerwin, Chicago, Ill., assignor to Welding Service, Inc., Chicago, Ill., a corporation of California

Application July 20, 1945, Serial No. 606,242

11 Claims. (Cl. 134—172)

1 This invention relates to quenching apparatus used in rail end hardening.

In the performance of the quenching step in a rail end hardening process performed on abutting rail ends lying in track, it is necessary to flow equal quantities of water concurrently in opposite directions from the rail joint for a selected period of time. The principal object of this invention is to provide a nozzle and companion equipment that will provide such flow.

A second object of this invention is to combine in a single water box designed to span a track rail joint a centrally positioned opposed direction nozzle while at the same time preventing substantial loss of fluid through the gap between the two rail ends. In existing practice, two spaced water boxes have been used, see Figure 6 of U. S. Patent No. 2,070,889 to Frickey, dated February 16, 1937. The gasket that provides the seal between the inside of the water box and the top of the rail, numbered 61 in the same figure, prevents the flow of cooling fluid to the very tips of the rail, and there has been a suggestion that the desired hardness has not been attained at these points of the rail tread. In the present invention, a single water box with a continuous seal or packing around its lower periphery is used and means are provided for substantially blocking the flow of fluid through the opening between the rail ends.

Another object of this invention is to relate the adapter frame (which itself is old in the art, see Fig. 1 of Frickey patent, 2,143,347) to accommodate the rail end quencher to various sizes of rails and to an associated opposed directional nozzle. Each size adapter carries guides for a nozzle suitable for use on a rail of a given size.

Another object of this invention is to hold the quenching apparatus tightly to the rail during the performance of the quenching step. The process invention contemplates the flowing of fluid onto the rail at comparatively high pressure, and this with the effects of steam formation causes undesirable vibration and movement of the water box. Features of this apparatus are magnets for holding the water box tightly to the rail during the quenching step.

Another object of this invention is to enable the operator to center the directional nozzle directly over the opening between the rail ends by feel rather than observation. One of the features of the invention is the mounting of a downwardly directed wedge on the bottom of the nozzle and transversely to the rail length. By setting the quencher on the two rail ends,

and moving it longitudinally until the wedge drops into the gap between the rail ends, the operator can exactly center the quencher over the joint without getting down on his hands and knees for visual examination.

There are other features which will appear in the description that follows. The invention is illustrated in two sheets of drawings comprising the following figures:

10 Figure 1 is a side elevation of the quencher;
Figure 2 is an end elevation thereof;
Figure 3 is a longitudinal sectional view of the quencher;

Figure 4 is a transverse, sectional view taken on the line 4—4 of Figure 1;

Figure 5 is a view of a portion of the top of the adapter frame showing its relationship to the nozzle and taken on approximately the line 5—5 of Figure 3;

20 Figure 6 is an enlargement of one face of the nozzle; and

Figure 7 is an enlargement of the nozzle showing the use of the positioning wedge.

Continuing to refer to the drawings, and particularly to Figure 1, the numeral 10 generally identifies a rail joint in track and this comprises a pair of abutting rail ends 12 and 14 held together by joint bars 16 and 18 together with suitable bolts such as nuts and bolts 19. The numerals 20 and 22 identify the respective rail balls while the numerals 24 and 25 identify the rail treads. Between the two rail balls is a gap 26 which varies in size from more than one-eighth of an inch in cold weather to nothing when the rails are in flush engagement in exceedingly hot weather. Applicant's quencher is ordinarily used on rails into which are cut the "McClary notch," see numeral 21 in Figure 2 of Reissue Patent 18,387, dated March 15, 1932 to A. W. McClary. This notch is illustrated by the sloping walls 28 and 30 in Figure 7. The notches actually used today are not quite as large as those illustrated in the McClary patent.

Applicant's quencher consists of a frame 32 made of a non-conductive material such as aluminum, and into the top of this are cut three circular openings 34, 36 and 38, referring to Figure 3. The frame 32 carries at either end two upright members 40 and 42 connected by a handle 44. The frame is supported on the rail by two magnets, each of which, referring to Figure 2, is seen to comprise two pole pieces 46 and 48 connected by a coil 50 mounted on a core 52. The bottoms of the corresponding pole members 46 and 48 are cut in a plane substan-

55

tially tangent to the line on the rail ball which each pole piece would normally engage. The bottoms of these two pole members 46 and 48 may be shaped transversely of the rail along a curve conforming to the top transverse cross section of the rail, but the flat tangential surfacing is easier and about as effective. The pole pieces are fastened to the non-magnetic frame member 32 by bolts such as 53.

Returning to Figure 3, 54 identifies a water box which is suspended from the frame 32 by four bolts 56, 58 and 60, the fourth bolt not appearing in any figure. These four bolts have a slide fit in the frame 32 so that the water box may be reciprocated vertically with respect to the frame. A spring such as 62 positioned around each of these bolts, thrusts the water box 54 downwardly away from the frame 32. Mounted at each inside end of the water box is an outlet pipe, being 64 and 66, each of which carries a check valve 68. These outlet pipes are rigidly fixed in the water box so that their bottoms are in approximately the plane that passes through an adapter frame 70, shortly to be described. The two outlet pipes project upwardly through the openings 34 and 38 in the frame member and have connected to their upper ends flexible delivery lines 72 and 74 which lead to a circulatory pump.

Centrally of the top of the water box is an opening 76 in which is mounted an inlet pipe 78 which carries a shoulder 80. This shoulder limits downward movement of the pipe, the pipe having a slide fit in the opening 76. The bottom of the pipe 78 is threaded (see Fig. 7) and to it is attached a small box, which will be referred to herein as the nozzle 82. The nozzle 82 is oblong in shape with a central chamber 84. An elongated downwardly directed passageway 86 opens into a horizontal passageway 88, see also Figures 4 and 6. Transversely of the bottom of the nozzle 82 is a wedge 90, see Figure 7, which has on each side of it substantially horizontal shoulders 92 and 94. These horizontal shoulders are important in that they hold the delivery openings 96 and 98 at a selected point above the rail, it being desirable to cool the tip of the rail a little less decisively than the adjacent portions. What is desired is a rail tip a little harder than what is obtained where the packing (see numeral 67 of Figs. 6 and 7 of Frickey et al., No. 2,070,889) rests on the tip and prevents any substantial flow of fluid thereagainst and the other extreme of flowing the fluid directly onto the rail tip which, because it has a smaller adjacent portion from which to withdraw heat than other parts of the rail ball, becomes excessively hard. But for the horizontal shoulders 92 and 94, in the case of a joint where the rails are widely separated and this separation is accentuated at the tread by the McClary notch, the nozzle might drop well down in so that the discharge openings 96 and 98 would flow directly onto the rail tips.

Returning to Figure 3, a spring 100 urges the nozzle downwardly so that when the quencher is lifted clear of the rail, the shoulder 80 will engage the top of the water box. The upper end of the inlet pipe 78 projects through the opening 36 in the frame 32 and has connected thereto a flexible water-oil delivery line 102.

Continuing to refer to Figure 3, fastened to the bottom of the water box 54 is an adapter frame 70 which is held in position by bolts such as 106. Directed downwardly from the adapter

frame 70 is a perimetric packing gland or seal 108 which, referring to Figure 6, embraces substantially the entire tread of the rail. Returning to Figure 3, interiorly of the adapter frame 70 are two sets of shoulders, the first set bearing numerals 110 and 112, and now referring to Figure 5, the second set bearing numerals 114 and 116. These shoulders are adapted to provide a loose fit for vertical movement of the nozzle 82, so that the adapter frame cooperates with the water box 54 to maintain the nozzle 82 in proper position. This is to be contrasted with the arrangement illustrated in Frickey Patent No. 2,143,347 where the incoming fluid is dropped from the top of the box so that it flows onto the rail and there is no need for exactly positioning the delivery nozzle with respect to the rail.

The perimetric seal 108 should close for a given sized rail just that area which experience has demonstrated produces the desired hardness gradient by the use of the particular equipment. Over or under heating and over or under quenching for comparatively small portions of time, a matter of seconds, may produce an unwanted hardness gradient. It has been found desirable to maintain proportionate the areas of the rail ball treads that are actually quenched with water-oil for respective sizes of rails. For this reason, the adapter frames are of various sizes, and because it is desirable to flow the sheet of water-oil away from the rail end for substantially the full width of the ball tread, applicant provides a nozzle having a width proportionate to the width of the rail ball, with complementary guide elements in the adapter frames.

Referring to Figure 6, it will be appreciated that there will be certain leakage of fluid down into the gap between the rail ends at a point such as 118. The wedge 90 together with the associated shoulders 92 and 94, see Figure 7, stops much of this, but in actual use the generation of steam seems to assist the applicant in obtaining the low loss of fluid that is desired. At the point 118, the fluid is a recirculated fluid which has either flowed back of the sides of the stream coming out of the opening 88 or back over the top of it. It has been considerably heated and when it reaches the very hot part of the rail adjacent the edge it forms a steam which tends to keep the liquid itself in the box.

It is important to understand that this apparatus operates with comparatively little water-oil in the box 54. Whereas existing equipment quite frequently operates with the box nearly full, it is intended that the fast moving streams do a great deal of the cooling here and that the cooling effect be graduated downwardly from the rail end inversely proportional with the rising temperature of the cooling stream as it moves toward the two outlets 64 and 66.

It will be appreciated that the above structure obtains the major object of this invention because it uses a single inlet pipe which delivers the flow into a single collection chamber 84, from which leads the delivery opening 86 which in turn divides into the two delivery openings, 96 and 98. The liquid from each opening is directed slightly downwardly so as to impinge upon the surface of the rail at points quite close to the nozzle.

In positioning the quencher over the rail joint, the operator simply seats it on the rail ball, and in so doing, the inlet box 54 will be pushed upwardly into the frame 32 and similarly the nozzle 82 will be pushed upwardly, the wedge 90 engaging one or the other of the rails. The op-

erator then moves the quencher longitudinally of the rail until the wedge 99 engages the notch 28, 30, at which time by merely feel, the operator knows that the nozzle is in exactly the right position. The switch energizing the magnets is then thrown and the quenching operation performed, ordinarily under the control of an automatic timer.

Mounted on the opposite sides of the water box 54 are pairs of positioning fingers 120, 122, and referring to Figure 4, 124, the last finger not being shown. At the bottom of each finger is a little lug 126. The radii on the upper edges of the rail balls cam the lugs 126 outwardly against the compressing spring action of the fingers 120 to 124 which fingers thereby perform the lateral positioning function while the longitudinal positioning function is performed by the wedge 99.

Having thus described my invention, what I claim as new and wish to secure by United States Letters Patent is:

1. A rail end quencher comprising a frame, means connected to the frame for supporting said frame on the balls of two abutting rail ends in a track joint, a single liquid delivery nozzle having oppositely, outwardly directed, substantially equally sized orifices aligned longitudinally of the rails and mounted on the frame with said orifices slightly above a line connecting the bottoms of the supporting means, and means on the nozzle for engaging the gap between two rail ends for quickly and accurately positioning the nozzle with respect to the rail ends.

2. A rail end quencher comprising a frame, means connected to the frame for supporting said frame on the balls of abutting rail ends in a track joint, a nozzle having oppositely, outwardly directed orifices aligned longitudinally of the rails and mounted on the frame with said orifices slightly above a line connecting the bottoms of the supporting means, and means for raising or lowering said nozzle with respect to the frame.

3. A rail end quencher comprising a frame, means connected to the frame for supporting said frame upon the balls of abutting rail ends of a track joint, a liquid delivery pipe mounted on said frame with its axis substantially vertical and reciprocable axially, a nozzle mounted on the delivery pipe and having two oppositely, outwardly directed orifices aligned longitudinally of the rails and mounted on the frame with said orifices slightly above a line connecting the bottoms of the supporting means, and a spring urging the nozzle downwardly against the rail, whereby the nozzle may freely engage the ball of the rail without being affected by the frame supporting means.

4. A rail end quencher comprising a frame, means connected to the frame for supporting said frame upon the balls of abutting rail ends in a track joint, a nozzle mounted on said frame and capable of vertical movement with respect thereto, said nozzle having a pair of oppositely, outwardly directed orifices aligned longitudinally of the rails and having like sized rectangular openings with the long side substantially parallel to the transverse top of the rail tread and the flow directed along the rail tread, and a wedge with its edge directed downwardly positioned on the bottom of the nozzle with said edge transverse to the length of the rails.

5. A rail end quencher comprising a frame, means connected to the frame for supporting said frame upon the balls of abutting rail ends in a track joint, a nozzle mounted on said frame so

that it can move vertically and having two oppositely, outwardly directed orifices having axes directed toward and along the upper surface of the respective rails, a substantially flat bottom on the nozzle having a width sufficient to span the gap between two abutting rail ends in a standard track joint, and a downwardly projecting lug on the bottom of the nozzle for loosely engaging the gap between the two rails, whereby the nozzle will act as a dam against the flowing of liquid down the gap between the two rail ends.

6. A rail end quencher comprising a rectangular box having an open bottom, means around the periphery of the bottom for sealing the bottom of the box to a selected portion of the tread of each of two abutting rail ends in a rail joint within the plan dimensions of the box, a vertically movable nozzle disposed within said box, oppositely, outwardly directed, like sized orifices in the base of said nozzle aligned longitudinally of the rails and cooperating with the rail for directing equal sized streams of water in a plane substantially parallel to that of the rail treads, and a liquid outlet at each end of the box at a level above the bottom of the box approximating that of the two orifices.

7. A rail end quencher comprising a box having an open bottom and a closed top, a liquid inlet line mounted on said box, an adapter frame removably attached to the bottom periphery of said box and having a downwardly directed seal, a vertically movable nozzle mounted on said liquid inlet line, and guide means on the adapter frame for engaging said nozzle.

8. A rail end quencher comprising a box having an open bottom, means for sealing the bottom periphery of the box to a selected portion of the tread of each of two abutting rails in a rail joint, means within the box and cooperating with the rails for directing oppositely, outwardly two substantially equal streams of fluid substantially parallel to the rail treads toward the respective box ends, means for removing the fluid from the box, and electromagnetic means mounted on the box and engageable with the rail balls for compressing the sealing means between the bottom periphery of the box and the rail balls to avoid loss of fluid.

9. A rail end quencher comprising a frame, electromagnets suspended from said frame and adapted to support said frame on the ball of a rail, a box having an open bottom and mounted movably in a vertical line beneath said frame, sealing means around the open bottom periphery of said box for engaging the tread of each of two abutting rails in a rail joint, a vertically movable nozzle having oppositely, outwardly directed orifices aligned longitudinally of the rails and mounted within said box, and means at each end of the box for withdrawing fluid therefrom.

10. A rail end quencher comprising a frame, electromagnets suspended from said frame and adapted to support said frame on the ball of a rail, a box having an open bottom and mounted movably in a vertical line beneath said frame, sealing means around the open bottom periphery of said box for engaging the tread of each of two abutting rails in a rail joint, a vertically movable nozzle having oppositely directed orifices mounted within said box, means at each end of the box for withdrawing fluid therefrom, and a pair of downwardly projecting fingers, each fastened on one side of the box, and having their lower ends engageable with the side walls of the rail balls

for centering the box laterally with respect to the rail.

11. A rail end quencher comprising a frame, electromagnets suspended from said frame and adapted to support said frame on the ball of a rail, a box having an open bottom and mounted movably in a vertical line beneath said frame, sealing means around the open bottom periphery of said box for engaging the tread of each of two abutting rails in a rail joint, a vertically movable nozzle having oppositely directed orifices mounted within said box, means at each end of the box for withdrawing the fluid therefrom, a pair of downwardly projecting fingers, each fastened on one side of the box, and having their lower ends engageable with the side walls of the rail balls for centering the box laterally with respect to the rail, and means mounted on the bottom of the nozzle for engaging the gap between the rail ends.
